Primary Examiner — Robert M Spear(74) *Attorney, Agent, or Firm* — Robert N. Lipszik(57) **CLAIM**

The ornamental design for a tire, as shown and described.

DESCRIPTION

FIG. 1 is a perspective view of a tire showing our new design, it being understood that the pattern repeats uniformly throughout the circumference of the tire;

FIG. 2 is a front elevational view thereof;

FIG. 3 is a right side elevational view thereof;

FIG. 4 is a left side elevational view thereof; and,

FIG. 5 is an enlarged fragmentary front elevational view thereof.

In the drawings, the broken lines immediately adjacent the outer edges of the tire shoulder represent boundaries of the claim; the broken lines showing the tire tread, sidewall and inner bead in FIGS. 1 through 5 depict environmental subject matter and form no part of the claimed design.
